UNITED STATES PATENT OFFICE.

JOHN BECK, OF ASHLAND, WISCONSIN.

REFRIGERATOR.

Application filed July 26, 1921. Serial No. 487,713.

To all whom it may concern:

Be it known that I, JOHN BECK, a citizen of the United States, and a resident of Ashland, in the county of Ashland and State 5 of Wisconsin, have invented a new and Improved Refrigerator, of which the following is a description.

My invention relates more particularly to the ice rack of a refrigerator and in association therewith a novel arrangement to carry off the drip and to provide for an effective circulation of the air about the rack and its associated features, all of which will clearly appear as the description proceeds.

Reference is to be had to the accompanying drawings forming a part of this specification, it being understood that the drawings are merely illustrative of one example 20 of the invention.

Figure 1 is a vertical section of a refrigerator embodying my invention;

Figure 2 is a section on the line 2—2, Figure 1.

In carrying out my invention in practice, the refrigerator 10^b has ledges 16^a at the front and back, the lining 16^b preferably in practice curving over the curved under side of said cleats. Also, the lining above the 25 cleats extends horizontally as at 16^c over the cleats at the top and given the form of depending flanges 16^d laterally inward of the cleats. The lining material at the two opposite sides is formed into inclined deflectors 30 16^e. On top of the horizontal extensions 16^c of the lining are bracket irons 16^f of Z-shape presenting flanges 16^g. A rack 14^a rests on the flanges 16^g and permits the drip from the ice to fall through the rack. Below the 35 rack 14^a an inclined pan 21^a is provided preferably made of sheet metal and having a double bottom 21^b. The pan is supported on brackets 11^a at opposite sides and at different elevations, the pan at the bottom having a depending flange 21^c resting on said 40 brackets. The pan has a drain hole 21^d in which a short pipe length 25^a extends and

depends at the under side of the pan, said pipe telescoping in the drain pipe 24^a. The pan 21^a dips both longitudinally and laterally for the flow of water to the drain hole 21^d. A shelf 36 is shown in the lower pan 21^a and resting on protuberances 37 at opposite sides of the refrigerator.

The inclining of the pan 21^a facilitates 55 the circulation of air. The air circulates about the pan between the same and the rack, the air circulating circuit being below the ice rack.

The drip falling from the ice rack through 60 the circulating air results in gases and odors being absorbed by dripping water to be carried off with the water through the drain pipe. Also the air by circulating beneath and adjacent to the ice rack, is cooled to 65 about the same extent by a few inches of ice as with deeper ice.

I would state in conclusion that while the 70 illustrated example constitutes a practical embodiment of my invention, I do not limit myself strictly to the exact details herein illustrated, since manifestly the same can be considerably varied without departure from the spirit of the invention as defined in the appended claim.

Having thus described my invention, I 75 claim:

A refrigerator of the class described, comprising an upper and a bottom chamber, a rack between the chambers, ledges supporting the rack, said ledges being secured to the side wall of the refrigerator and presenting an inwardly extending curved underside for deflecting the vertically moving air laterally inward below the rack, and a drip pan below the rack in spaced relation therewith and in spaced relation with the side walls of the refrigerator forming an air passage of substantially equal depth throughout extending from one side of the pan over its upper face to the other side thereof.

JOHN BECK.
